UNITED STATES PATENT OFFICE.

JOHN M. FERRISS, OF NEW YORK, N. Y., ASSIGNOR TO THE HARRIMAN NATIONAL BANK OF THE CITY OF NEW YORK.

HAND DUPLICATOR OR STAMP.

Application filed April 14, 1925. Serial No. 23,153.

This invention relates to hand duplicators or stamps of the type in which a body member with a handle is used together with a stencil sheet, inking pad, and devices for positioning and locking the said stencil sheet and ink pad on the said body member.

The device of this application is in the nature of an improvement of the structure disclosed in my co-pending application, Serial Number 9909 in which I described and claimed a duplicator with an arched spring lid or cover.

I have also devised a new construction in the flanges on the upper inside walls of the diaphragm of the device, to prevent any leakage or overflow of ink from the interior of the said diaphragm.

To obtain a more positive locking of the ink pad and stencil sheet on the perforated diaphragm I have devised an improved construction of the upper portions of the said diaphragm carrying the lugs for engagement with the apertures in the ends of the said pad and stencil sheet.

My invention is simple and economical in construction, easy to assemble and use, and is particularly cleanly as no ink can leak or drip from its interior whether in or out of use.

Other advantages will appear in the following specification and in the drawings in which:—

Fig. 1 is a plan view.

Fig. 2 is a side view partly in section.

Fig. 3 is an end view partly in section.

Fig. 4 is an enlarged detail end view.

Fig. 5 is a view of the ink pad.

Fig. 6 is a view of the stencil sheet.

As shown, the perforated diaphragm A is of the usual curved type with a bottom wall 10, side walls 11—11, end walls 13—13, and perforations 12—12 in the bottom wall 10, over which the ink pad C and the stencil sheet D are positioned. The horizontal rectangular flanges 14—14 and similar vertical flanges 33—33 combine to form with the vertical upper portions of the diaphragm A a three sided well or channel extending entirely around the interior of the said diaphragm whereby the device can be laid on its sides or ends and no ink can leak or seep to its exterior.

To position and lock the ink pad C and the stencil sheet D on the diaphragm A, pad clamps 15—15 hinged at 17—17 to the end

wall 23, and stencil clamps 16—16 hinged in the same way at 18—18 are provided, the slots 39—39 in the reinforcing strips 38—38 at either end of the ink pad C engaging with the bosses 27—27 on the upper exterior portion of the side walls 11—11 and the slots 40—40 in the said reinforcing strips and the slots 43—43 in the reinforcing strip 42 of the stencil sheet D engaging with the bosses 28—28 arranged beneath and in staggered relation to the bosses 27—27.

If desired, one end of the stencil sheet D may be left free, so that when the opposite end is locked onto the bosses of the diaphragm the stencil sheet may be rolled into 70 position to obtain a snug fit without wrinkles. I also have found that the application of a thin sheet of rubber 34—34 on the outer surfaces of the reinforcing strips 38—38 will act to prevent the said strips from becoming 75 slippery from excess ink and thereby tend to permit small wrinkles to occur in the stencil sheet D after being in use for a short period of time.

It will be noted that in this construction 80 the portions 11—11 of the diaphragm A upon which the pad clamps 15—15 and stencil clamps 16—16 lock the ink pad and stencil sheet, are slightly depressed inwardly to form the angles 32—32, so that on the exterior an increased locking grip on the said pad and stencil sheet is obtained when the clamps 15—15 and 16—16 are in closed position.

In the practical use of devices of this type, 90 the stencils are frequently changed so that new reading may be produced, but the ink pad will last a considerable time, and therefore it is desirable that the removal of the stencil sheet be easy of accomplishment and 95 independent of the said ink pad. In this structure, stencil sheets may be removed and replaced without any disturbance whatsoever of the ink pad. In section the pad clamps 15—15 are rectangular in shape, with slots 29—29 100 and for engagement with the bosses 27—27 and at their free ends they are bent to form spring catches 24—24 with finger grips 19—19, and apertures 21—21 for engagement with the lugs 26—26 on the end wall 105 13 of the diaphragm A.

In a similar manner the stencil clamps 16—16 are hinged at 18—18 and are provided with the slots 30—30 for engagement with the bosses 28—28. These clamps also have 110

the spring catches 25—25, the finger grips 20—20 and the apertures 22—22 for engagement with the lugs 26—26.

As is obvious, an ink tight closure is formed by the junction of the horizontal top walls 15—15, the upper edges of the ink pad C and the longitudinal edges of the lid B, and the longitudinal upper edges of the side walls 11—11. The horizontal top flanges of the stencil clamps 16—16 extend outwardly to form a guide or register against which the material on which the printing is to be done may be positioned to secure perfect alignment with what is cut on the stencil sheet.

The closure lid shown herewith is of the usual type with a handle 31 and is adapted to form a snug inktight interlocking on the flanges 14—14 and under the horizontal flanges on the pad clamps 15—15.

To aid the operator to determine the relative position of the cut lines in the stencil sheet and the location in which they will appear on the printed sheet a series of grooves 36—36 are cut in the end wall of the diaphragm A. (See Fig. 3).

The details of the inkpad C are shown in Fig. 5, the body portion thereof being indicated at 37, reinforcing strips 38—38, the rubber protecting film 34, and the perforations 39—39 for engagement with the bosses 27—27 and the second row of perforations 40—40 for engagement with the bosses 28—28 on the diaphragm A.

In a similar manner the stencil sheet D is shown in Fig. 6, the free end being indicated by 41, the reinforced end by 42 and 43—43 being the slots for engagement with the bosses 28—28 on the diaphragm A.

The diaphragm A is provided with the bosses 28—28 on both of its side walls 11—11 for engagement with the series of slots 40—40 at either end of the ink pad C and also to make it possible to position the stencil sheet D on either side of the diaphragm by engagement between the said bosses 28—28 and the slots 43—43. It is obvious that the stencil sheet D could be made with the strip 42 and the slots 43—43 at both ends if desired.

I do not desire to limit myself strictly to the preferred form shown herewith, as there are a number of other ways in which I could accomplish the desired result without departing from the spirit of my invention.

I claim:

1. In a duplicator the combination of the following elements; a diaphragm comprising end walls, an arcuate perforated bottom wall, side walls mounted on the upper longitudinal edges of the said bottom wall and having a plurality of bosses on their outer surfaces, and ink retaining means comprising a plurality of rectangular flanges mounted on the upper surfaces

of the said side and end walls; an ink pad; a stencil sheet; pad clamping members; stencil clamping members, and a closure lid adapted to be locked on the upper surfaces of the said diaphragm by the said pad clamping members. 70

2. In a duplicator the combination of the following elements; a diaphragm comprising end walls, an arcuate perforated bottom wall, vertically disposed side walls mounted on the said bottom wall and inside of the outer line thereof, a plurality of bosses on the outer surfaces of the said side walls; ink retaining means comprising a plurality of rectangular flanges mounted on the upper surfaces of the said side and end walls; an ink pad; a stencil sheet; pad clamping members; stencil clamping members; and a closure lid adapted to be locked on the upper surfaces of the said diaphragm by 80 the said pad clamping members. 75

3. In a duplicator the combination of the following elements; a diaphragm comprising end walls, an arcuate perforated bottom wall, vertically disposed side walls mounted on the said bottom wall and inside of the outer line thereof; ink retaining means comprising a plurality of rectangular flanges mounted on the upper surfaces of the said side and end walls; a plurality of bosses on the outer surfaces of the said side walls; an ink pad and stencil sheet provided with slots adapted to engage with the said bosses; pad clamping members hingedly secured to the said diaphragm; stencil clamping members hingedly secured to the said diaphragm; and a closure lid adapted to be locked on the upper surfaces of the said diaphragm by the said pad clamping members. 90 95

4. In a duplicator the combination of the following elements; a diaphragm comprising end walls, an arcuate perforated bottom wall, vertically disposed side walls mounted on the said bottom wall and inside of the outer line thereof; ink retaining means comprising a plurality of rectangular flanges mounted on the upper surfaces of the said side and end walls; a plurality of bosses on the outer surfaces of the said side walls; an ink pad and stencil sheet provided with slots adapted to engage with the said bosses; pad clamping members hingedly secured to the said diaphragm and provided with slots adapted to engage with the said bosses on the side walls and thereby lock the ink pad in position; stencil clamping members hingedly secured to the said diaphragm and provided with slots adapted to engage with the said bosses on the side walls and thereby lock the stencil sheet in position; and a closure lid adapted to be locked on the upper surfaces of the said diaphragm by the said pad clamping members. 110 115 120 125

JOHN M. FERRISS.
